UNITED STATES PATENT OFFICE.

FRANK W. ROBINSON, OF READING, PENNSYLVANIA, ASSIGNOR TO THE NOLDE & HORST CO., OF READING, PENNSYLVANIA, A CORPORATION OF PENNSYLVANIA.

TUCKING AND DROP-STITCH MECHANISM FOR KNITTING MACHINES.

1,402,379.

Specification of Letters Patent. Patented Jan. 3, 1922.

Application filed May 21, 1919. Serial No. 292,577.

To all whom it may concern:

Be it known that I, FRANK W. ROBINSON, a citizen of the United States, residing at the city of Reading, in the county of Berks and 5 State of Pennsylvania, have invented certain new and useful Improvements in Tucking and Drop-Stitch Mechanism for Knitting Machines, of which the following is a specification.

10 My invention relates to circular knitting machines, and it consists in improved mechanism providing for continuous knitting with desired vertical stripings spaced around the whole circumference, as of the leg portion of 15 a stocking, or upon a part only of such circumference as is desired in a stocking foot. The invention is fully described in connection with the accompanying drawing and particularly pointed out in the claims.

20 Fig. 1 is a diagrammatic view of a knitting cam mechanism embodying my present invention.

Fig. 2 illustrates a circular series of needles having different lengths of butts operative by said cam mechanism as herein-after described; certain thereof with relatively long latches being indicated by heavier lines.

Fig. 3 is a detail plan view of the butt en-gaging end portion of the supplemental long-latch clearing cam employed.

Fig. 4 indicates a stocking product of my improved mechanism; and Fig. 5 the lace-stripe effect particularly provided for.

35 Fig. 6 further indicates the differences in needle latches and butts diagrammatically illustrated in Fig. 2.

The circular series of needles indicated in Fig. 2 is divided into approximately half-40 circle series, of long-butt needles *a* and short-butt needles *b* respectively, for circular or reciprocative knitting as usual in the production of stockings. Certain of these needles, as *a' a'* of the long butts and *b' b'* of the 45 short butts, differ from the others in being provided with relatively long latches adapted to hold their loops unless special clearing movement is imparted to them; and drop stitch effects are provided for, as indicated, 50 by the omission of determined needles of the long butt series as at *a'' a''*, and by providing determined needles *b'' b''* of the short butt series with butts of intermediate length adapting them to be thrown into or out of 55 knitting action as desired.

By proper operation of needles formed and arranged in such manner as is indicated, tucking effects may be produced, in connection with drop stitch effects as desired; and the particular purpose of my present invention is to provide for so operating the needles as to enable the continuous production of such tucking effects, preferably in connection with drop stitches so as to produce lace stripes as indicated in Figs. 4 and 5, upon 60 the entire leg portion of a stocking as is generally desired, and upon the upper portion only of the tubularly knitted foot.

The general arrangement and operation of cam mechanism for directly actuating the 70 needles being well known, my present improvements may be clearly explained in connection with the diagrammatic showing of Fig. 1, where the usual center cam is indicated at 2, and the usual left hand latch clearing cam at 3. In connection with the corresponding right hand latch clearing cam 4 is provided a long-latch clearing cam 5 adapted to be thrown into or out of cooperative relation therewith as particularly set 80 forth in my pending application Ser. No. 292,262 filed Apr. 24, 1919, so as to either raise all the needles sufficiently to clear their loops as required for ordinary knitting, or to cause determined loops to gather upon the 85 long latch needles as desired for "tucking."

Below the normal needle run-way 10 is provided a lower run-way 11 connected by reversely inclined branches 12, 13, which branches are guarded respectively by a movable dividing cam 14—15 in connection with a fixed relowering cam 16, and by a return switch cam 17, as shown in my Patent No. 1,339,715, dated May 11, 1920. In my present improved construction I provide additional cams 20, 21, 22, which may be combined in a single device as indicated so as to be jointly movable into and out of the needle path; the face of cam 20 being set back so as to loweringly engage the longer butt needles only; while cam 21 is arranged to raise the shorter butt needles sufficiently to clear loops from the long latched ones also (for ordinary knitting as in the lower foot portion), and cam 22 to relower the same; different courses taken by the respective needles as controlled by the complete cam mechanism shown, being indicated in Fig. 1 by distinguishing lines referred to in the following description.

All of the needles follow the usual knitting course when the movable cams 5, 14-15, and 20-21-22 are retracted; the cam 4 however being adapted to raise only the ordinary latch needles sufficiently to clear their loops. In starting to knit a stocking as indicated in Figs. 4 and 5, dividing cam 14-15 may be thrown into the needle path so as to lower the intermediate butt needles 10 b^2 into the lower run-way 11 for forming drop stitches, the short butt needles freely passing the cam portions 15, and the long butts being only temporarily deflected from the normal path by the cam portion 14 and 15 returned thereto by the relowering cam 16. During the knitting of the leg portion of the stocking the ordinary latch needles a and b will knit regularly, while the long latch needles a' and b' will hold their loops unless 20 specially raised sufficiently to release them; which additional raising is effected by throwing in the long latch clearing cam 5 at determined intervals so as to gather the retained loops in tucks, which show in connection with the drop stitches as indicated 25 in Fig. 5. Such tucked striping effects upon the entire leg portion, may be continued upon the upper foot portion of the stocking in connection with regular knitting of the lower foot portion, as follows: For reciprocative knitting of the heel, and, subsequently of the toe, the long butt needles are temporarily thrown out of action as usual; but during such knitting and also the knitting 30 of the tubular portion of the foot, all of the short butt needle series are operated as in regular knitting. This is accomplished by first returning the lowered intermediate butt needles b^2 to action by means of the 35 return switch cam 17, and knitting the heel with the movable cam 5 set in position to clear all the needles. The tubular knitting of the foot is then effected with the long butt needles thrown into action; these then requiring to be tuckingly operated as before 40 by intermittent movement of the long latch clearing cam 5. The short butt needles however must be simultaneously operated to constantly clear all their loops for regular 45 knitting. This is effected by throwing the supplemental cams 20-21-22 into operation, the effect being to specially operate the short butt needles, which have not been cleared by the intermittently acting cam 5, 50 while leaving the long butt needles subject only to the intermittent action of said cam 5 as in the knitting of the leg portion of the fabric. The continuance of the tucking ornamentation upon one circumferential 55 portion, in connection with regular knitting of the corresponding portion, which is thus

provided for, enables the economical production of a very attractive and desirable product.

What I claim is:

65

1. In a knitting machine comprising needles having butts of different lengths and certain of the long and short butt needles provided with relatively long latches; main latch clearing cams adjustable to clear all of 70 the needles or the short-latch needles only, and supplemental latch clearing cams effectively operative upon the shorter-butt needles only.

2. In a knitting machine comprising 75 needles having butts of different lengths and certain of the long and short butt needles provided with relatively long latches; knitting cams including a main latch-clearing cam effectively operative upon the ordinary 80 latch needles only, a long-latch clearing cam intermittently operative upon all the needles, and supplemental long-latch clearing cams effectively operative upon the shorter butt needles only.

85

3. In a knitting machine comprising a half-circle series of long-butt needles and a half-circle series of short-butt and intermediate-butt needles, certain of the needles being provided with long latches; knitting 90 cams including a main latch-clearing cam effectively operative upon the ordinary latch needles only, a long-latch clearing cam intermittently operative upon all the needles, supplemental long-latch clearing cams effectively operative upon the shorter-butt needles only, and means for throwing said intermediate-butt needles into and out of knitting action.

95

4. In a knitting machine comprising 100 needles having butts of different lengths and certain of the long and short butt needles provided with relatively long latches; knitting cams including a long-latch clearing cam comprising a long-butt lowering member and short-butt raising and lowering members jointly movable into and out of the needle path.

105

5. In a knitting machine comprising needles having butts of different lengths 110 and certain of the long and short butt needles provided with relatively long latches; knitting cams including a main latch-clearing cam effectively operative upon the ordinary latch needles only, a long-latch clearing cam intermittently operative upon all the needles, and supplemental long-latch clearing cams effectively operative upon the shorter butt needles only and adapted to be moved into or out of operative position.

115

In testimony whereof I affix my signature.
FRANK W. ROBINSON.
